UNITED STATES PATENT OFFICE.

HIYOZO KAWATE, OF SEATTLE, WASHINGTON.

INTERNAL-COMBUSTION ROTARY ENGINE.

1,358,450.

Specification of Letters Patent.

Patented Nov. 9, 1920.

Application filed September 15, 1919. Serial No. 323,952.

To all whom it may concern:

Be it known that I, HIYOZO KAWATE, a subject of the Emperor of Japan, and resident of the city of Seattle, county of King, 5 and State of Washington, have invented certain new and useful Improvements in Internal-Combustion Rotary Engines, of which the following is a specification.

My invention relates to rotary engines, 10 and more particularly to a rotary, internal combustion engine, wherein a series of rotors operate revolvably within an oppositely rotatable casing, under the driving combustion of fuel charges that are admitted into the explosion chambers, ignited, 15 and discharged in proper sequence to cause rotation of a power transmission shaft.

The principal object of the invention is to provide an engine of this character comprising such novel features of construction 20 in the rotors and their casing and in the mechanism whereby fuel charges are admitted into and discharged from the combustion chambers of the engine, together 25 with means for maintaining the circulation of a cooling medium and lubricant about the operating parts that an efficient and reliable engine is provided.

It is also an object of the invention to 30 provide for reverse driving of the power shaft through the intermediary of a novel clutch mechanism that is automatically adjustable, resultant to the setting of certain 35 brake bands, for individually controlling rotation of the rotors or the casing, whereby, when either the rotors or casing, which operate in opposite directions, are held against rotation, the one that is free to rotate will drive the power shaft in a like 40 direction.

In accomplishing these objects I have provided improved details of construction, the preferred forms of which are illustrated in the accompanying drawings, wherein—

45 Figure 1 is a longitudinal, vertical section taken centrally through an engine embodying the present invention.

Fig. 2 is a transverse, vertical section of the same, on the line 2—2 of Fig. 1.

50 Fig. 3 is a reduced view, illustrating the manner in which the supply chamber piston is moved inwardly to transfer a fuel charge to the outer side thereof.

Fig. 4 is a similar view illustrating the 55 relation of the rotor piston, the chamber piston and abutment in the explosion

chamber immediately after the rotor piston has dropped from the abutment.

Fig. 5 is an end view of the engine showing the connection of the fuel inlet and exhaust pipes, the water circulation pipes and lubricant conduit with the stationary end plate.

Fig. 6 is a detail face view of the clutch mechanism.

Fig. 7 is an enlarged sectional view of a part of the clutch mechanism.

Fig. 8 is an enlarged detail view of a rotor piston.

Fig. 9 is a detail side view of the same.

Fig. 10 is a transverse sectional view of a two piston engine equipped with three explosion chambers.

Fig. 11 is a detail sectional view, illustrating the mounting of the annular ring whereby electrical connection is provided 75 between one terminal of the induction coil to the current supply wire.

Referring more in detail to the drawings—

1 designates an axial power transmission shaft which may be revolvably mounted in any suitable supporting members, as by the standards 10, to permit proper operation and support of the parts carried thereby 85 and whereon a pulley 11, or other means, may be mounted to make possible the transmission of power therefrom.

Revolvably mounted on the shaft 1 are a plurality of circular rotors 12 which rotate 90 as a unit and are secured relative to each other by tie bolts 13 extended therethrough. These rotors operate within an exterior rotor casing 14, cylindrical in form, and of sufficiently greater diameter than the rotors, 95 that annular combustion chambers 15 are provided within the casing, the explosion chambers for the individual rotors being separated by annular division plate 16 which seats at the inner periphery within 100 an annular groove 17 provided between the rotor sections and at its outer edge is securely bolted to the casing.

The casing 14 is independent of the rotors and may revolve freely on the shaft 1 in a 105 direction opposite to the direction of the rotors. At one end it has an extension 18 wherein a clutch mechanism, presently described, is located to effect the transmission of power from the casing or rotors to the 110 shaft 1. The outer one of the connected rotors 12 is provided on the face opposite

the clutch mechanism with an annular rib 20 whereto a brake drum 21 is fixed by bolts 22.

Mounted about the drum 21 and also 5 about the casing 14 are brake bands 23 and 24 respectively which may be tightened or loosened by any suitable devices (not shown) to prevent or permit the same to rotate. It is apparent that, since the rotors 10 operate in opposed relation to the casing parts, if the casing is held against rotation and the rotors are left free to turn, then, combustion of fuel within the explosion chamber will drive the rotors, while, if the 15 order of setting the brakes is reversed, the casing will be driven in a direction opposite to that in which the rotors operate.

Since an engine of this character may comprise any desirable number of rotors 20 and parts operating in conjunction therewith, all of which would be identical in construction and operation, only one of the rotors will be described herein in detail, with the understanding that the description 25 relates equally to all employed.

Located within each annular explosion chamber 15 is an abutment or head 30, preferably formed integral with the casing, and which for a short distance entirely closes 30 the chamber. At one side this abutment has an inclined surface 31, extending from the outer casing wall to the periphery of the rotor and at its opposite end has a perpendicular wall or abutment 32 which serves in 35 opposed relation to and in conjunction with a piston 4, which is mounted in the rotor 12, as presently described, to form an inclosure of relatively small volume wherein fuel charges are exploded to effect operation of 40 the engine.

Within the body of each rotor is a fuel storage chamber 40 which at its inner side has a channel 41 opening thereto that opens at all times at its opposite end within 45 an annular channel 42 in a disk or end face plate 43 at one end of the engine; the plate 43 being free from the shaft 1 and rotor, and is held in position within the annular end flange 20 by means of exhaust and fuel 50 inlet pipes connected therewith, as shown particularly in Fig. 5.

Fuel is admitted from a source of supply (not shown) into the storage chamber 40 through a supply conduit 45, which supplies 55 two distributing conduits 46, Fig. 5, that discharge into the annular channel 42. The channel 42 is concentrically arranged with respect to the rotor so that there is continuous communication with the channel 41. 60 From the annular channel 42 the fuel enters the channel 41 and is drawn by suction into the chamber 40 through a spring-closed valve 47, located at the outlet of the channel and opening into the chamber and adapted 65 to prevent any back flow of fuel.

Operating within the chamber 40 toward and from the valve 47 is a piston 48 which at all times is yieldingly urged outwardly by a pair of compression springs 49 mounted within guide tubes 50, which at their 70 outer ends are fixed to the piston and at their inner ends slide within bores 51 within the body of the rotor.

The piston 48 has a spring-closed valve 52 therein through which fuel may pass as the 75 piston moves inwardly, and at the outer side of the chamber is a passage 53 having a valve 54 therein through which the fuel is forced from the chamber 40 into the explosion chamber 15 as the piston moves out- 80 wardly.

Operation of the piston 48 is accomplished as the rotor or casing rotates, through the intermediacy of the piston 4; the latter being slidably mounted within the rotor on a 85 radial line through its center and fitting at its outer end between the walls of the combustion chamber and against the outer casing wall in close contact to prevent leakage.

The piston 4 is urged outwardly by means of a coiled spring 55, Fig. 2, which operates within a guide tube 56, that is fixed to the piston 48 and is slidable within a bore 57 in the piston 4.

Referring particularly to Figs. 3, 4 and 2, which in the order named show successive positions of the chamber and rotor pistons during a cycle of the engine, it will be noted that as the rotor rotates, the outer end of the piston 4 travels up the inclined face 31 of the head 30, causing the piston 48 to be forced inwardly against pressure of the springs 49, causing a fuel charge that had previously been drawn into the 105 chamber 40 to be forced through the valve 52 to the opposite side of the piston. As the rotor continues to move forwardly, the piston 4 passes from the head 30, thereby releasing the piston 48, so that the latter moves under pressure of the springs 49 to discharge the fuel charge through the 110 valved channel 53 and into the closed chamber formed between the head 30 and piston 4, where it is immediately ignited.

The charges of burned fuel are exhausted through a channel 58 in the rotor body; the channel having an enlarged end opening immediately forward of the piston 4 and a discharge end communicating, as does the 120 fuel inlet passage, with an annular channel 59 in the face plate 43, whereto an exhaust conduit 59' is connected. It is apparent that exhaust fuel charges ahead of the piston 4 will be forced from the explosion chamber 125 as the piston nears the head 30.

Fuel charges are ignited at the proper time by use of a spark plug, as indicated at 60, which is threaded into the wall of the passage 53, and is electrically connected 130

through a wire 60' to the rotor body within a secondary winding of an induction coil 61, that is located within the rotor body and insulated therefrom. The induction coil is supplied with electricity by circuit wires 62 and 63, which are connected thereto, as presently described.

The coil 61 consists of a primary and secondary winding and has one of the terminals of the primary winding extended through an insulated tube into rubbing contact with an annular ring 62', which is set within a groove 62^a in the inner face of the end plate 43, and concentric with the shaft 1.

This ring is insulated from the plate and is electrically connected with the circuit wire 62, as illustrated in Fig. 11.

The opposite terminal of the primary winding is insulated from the rotor body and is exposed in the face of the chamber 40. An insulated connection 65 is mounted in the rotor body, with its opposite ends exposed at the face of the rotor and at the bottom face of the storage chamber.

The circuit wire 63 is grounded to the engine casing and serves to complete the circuit through the coil 61 only when the exposed ends of the terminal wire of the primary winding and the connection 65 are electrically joined. This is effected by a connecting member 66 that is carried by but insulated from the piston 48, when the piston is at its outer limit and the outer end of the connection 65 has moved into engagement with the upper face of the head 30.

Since the induction coil and the terminal windings are all insulated from the rotor and engine casing, it is apparent that the spark plug will be affected only when the circuit is closed by the connecting member of the piston. This arrangement insures the complete exhaustion of a fuel charge from the storage chamber into the combustion chamber before ignition takes place and also insures that the explosion will take place at the proper time.

As the rotor is driven forwardly by the explosion of a charge acting against the rotor piston, a slight vacuum may be produced as the volume of the explosion chamber increases, and in order to avoid this I provide an inwardly opening valve 70 in the flat face 32 of the head wherethrough air may be admitted from the exterior of the casing. Such admittance of air not only prevents retarding the motor due to vacuum pressure, but also aids combustion.

To prevent any possible leakage between the rotors, the casing and pistons, the same are provided, as is necessary, with packing strips or rings, 71, as shown in Figs. 1, 2, 8 and 9.

The piston 4 is provided with a roller 72

which rolls within a seat at the outer end 65 of the piston, to lessen friction as the piston moves in engagement with the casing wall and up the inclined surface of the head 30. The roller 72 contains a spring which bears against the inner ends of plug-like 70 members inserted into the tubes to urge the same against the side casing walls.

At its upper end the piston has laterally extending lugs 73, Figs. 2 and 9, which are adapted to move within a coöperating air 75 pocket 74, in the base of the chamber 40, so that the piston is cushioned against jar or damage from hitting the casing wall.

The casing and rotors are water jacketed, as shown, and circulation of a cooling medium is provided for by the connection of supply and discharge pipes 8 and 80, Fig. 5, respectively, which communicate with semi-circular channels 81—81' in the plate 43; the said channels having a concentric arrangement with the rotors so that a plurality of passages 85, Fig. 1, will at all times communicate therewith. The passages 85 lead to the interior of the rotors and are there provided with branch passages 86 90 which lead to the water chambers of the rotors and with openings 87, which are adapted to pass in registration with a large number of passages 88, Fig. 2, which lead through the plate 16 to the water chambers 95 of the casing. Circulation may be forced by means of a pump or may depend on the natural circulation of heated water.

All moving parts are likewise lubricated through channels as shown at 89, Fig. 1, 100 which communicate with an annular channel 90 in the plate 43, to which a lubricant supply pipe 91 is connected.

Located within the extension 18 at the end of the casing, is a clutch mechanism, Figs. 105 1, 6 and 7, comprising a spool 9 which is keyed to the shaft 1 and which has opposite end flanges 92—92' and an intermediate threaded portion 93 whereon a ring 94 is threaded, and which is adapted to be moved 110 laterally in opposite directions a limited distance.

Fixed to the face of the rotor 12 adjacent the spool 9 is a plate 5 which moves with the rotor but free from the casing. The plate 115 5 has an annular extension 95 and the inner surface of this extension and the inner face of the outer end of the casing extension are provided with a plurality of ribs 96. The hub of the spool 9 is likewise provided with 120 a plurality of ribs 97 on opposite sides of the threaded portion.

Inclosing the spool hub on opposite sides of the ring 94 are a plurality of annular disks 98 which are alternately locked against 125 rotation relative to the spool, but which have a limited lateral movement.

Abutting the opposite faces of the ring 94,

are plates 99—99', which are of sufficiently greater diameter than the disks 98, that they interlock with the ribs 96 and that a number of coil springs 100, located within the space 5 about the disks, may bear thereagainst. The springs which engage the plate 99 bear at their outer ends against the end plate 18' of the casing and those which engage the plate 99' bear at their outer ends against the plate 5.

With the engine so constructed, the operation will be as follows: assuming first that the brake band 24 is tightened to retain the housing 14 against rotation and that the 15 rotors are free to rotate. As the piston 4 rides up the inclined face 31 of the head 30, the piston 48 will be moved inwardly against the base of the chamber 40. As the piston 4 drops from the head 32, the springs 20 49 actuate the piston 48 outwardly, which will cause fuel to be drawn through the supply conduits 45, 46, 42 and 41, and valve 47, to fill the chamber 40. A successive operation of the pistons advances this 25 charge through the piston valve 52 to the opposite side of the piston 48 and then through the passage 53 into the explosion chamber 15, where it is ignited, as previously described.

30 As the rotors continue to rotate, pressure of the springs 100 against the plate 99, which engages the ring 94, retains the latter against rotation, so that it travels inwardly along the threads and compresses the disks 35 on the inner side of the ring tightly together in frictional locking engagement, so that the plate 5 is thereby locked relative to the spool 9 and the latter, being locked to the shaft 1, causes the shaft to be driven 40 in the direction of the rotors.

To reverse this driving direction, the 45 brake band 24 is loosened and the band 23 tightened, to hold the rotors against forward movement. Explosion of fuel charges then drives the casing in a direction opposite to that of the rotors and the clutch mechanism operates to move the ring 94 outwardly to effect locking relation of the spool and casing extension, so that the shaft is 50 driven in the direction of the casing.

In Fig. 10 I have illustrated an engine wherein the rotors are provided with two pistons diametrically arranged with respect to the rotor and which operate over three 55 abutments. Such an arrangement provides six explosions during each revolution, thereby creating a very great amount of power.

While I have only shown an engine of two 60 rotors, it is apparent that any desired number of rotors may be employed by extending the casing accordingly, and I do not wish to be limited to the exact construction shown, as it is possible to make variations without 65 departing from the spirit of the invention.

I claim:

1. In a rotary internal combustion engine, in combination, a power transmission shaft, a rotor revolvably mounted on said shaft, a casing for the rotor revolvble on the shaft 70 and forming an annular combustion chamber, an abutment in said chamber, a radially movable rotor piston operable over said abutment, means for admitting and discharging fuel charges into and from the explosion chamber, brake means for selectively retaining the rotors or casing against rotation, and automatically adjustable clutch mechanism for effecting a driving connection between the shaft and rotating member. 75

2. In a rotary internal combustion engine, in combination, a rotor, a casing for the rotor forming an annular explosion chamber, an abutment in the chamber having an inclined face, a radially movable piston operable over said piston, said rotor having a storage chamber provided with fuel inlet and discharge passages, a valved piston operable inwardly in said chamber by the radial movement of said rotor piston 90 and outwardly by compression members to advance fuel charges into the explosion chamber and a yieldable means for retaining the pistons at their outer limits. 85

3. In a rotary internal combustion engine, 95 in combination, a power transmission shaft, a rotor revolvably mounted on said shaft, a casing for the rotor revolvble on the shaft and forming an annular combustion chamber, an abutment in the chamber having an inclined face, a radially movable piston operable over said abutment, said rotor having a storage chamber provided with fuel inlet and discharge passages, a valved piston operable inwardly in said chamber by 100 the radial movement of said rotor piston and outwardly by compression members to advance fuel charges into the explosion chamber, yieldable means for retaining the pistons at their outer limits, brake means for selectively retaining the rotors or casing against rotation, and automatically adjustable clutch mechanism for effecting a driving connection between the shaft and rotating member. 105

4. In a rotary internal combustion engine in combination, a rotor, a casing for the rotor forming an annular combustion chamber thereabout, an abutment in said chamber, a radially movable piston mounted in 120 said rotor and operable in said chamber over said abutment; said rotor having fuel inlet and exhaust passages therein opening into the explosion chamber adjacent opposite sides of said piston and opening at 125 their opposite ends to an end face of the rotor, a non-rotatable member fitted against the end of said rotor having annular channels therein continuously in communication with said discharge and inlet passages as 130

the rotor rotates and means for admitting and discharging fuel charges into said annular channels.

5. In a rotary internal combustion engine in combination, a rotor, a casing for the rotor forming an annular combustion chamber, a radially movable rotor piston operable within said chamber and over said abutment; said rotor having a fuel storage chamber therein, a suction piston operable in said chamber and having an outwardly opening valve; said suction having a fuel inlet passage opening thereinto at one side of the piston and having an outlet passage 15 at the opposite side of said piston, said suction piston being operable inwardly by radial movement of said rotor piston and yieldable members mounted within said rotor for urging said chamber and rotor piston 20 tons outwardly.

6. In a rotary internal combustion engine in combination a rotor, a casing for the rotor forming an annular combustion chamber, a radially movable rotor piston operable within said chamber and over said abutment; said rotor having a fuel storage chamber therein, a suction piston operable in said chamber and having an outwardly opening valve; said chamber having fuel 25 inlet and discharge passages leading therefrom at opposite sides of the piston, outwardly opening valves in said passages; said

suction piston being actuated inwardly by radial movement of the rotor piston as the latter engages the abutment, yieldable members mounted in said rotor to urge said suction piston outwardly and separate members mounted in said rotor piston engageable with the suction piston to urge the rotor piston outwardly in advance of the suction 40 piston and a cushioning means for retarding movement of the rotor piston.

7. In a rotary internal combustion engine, in combination, a rotor having a fuel storage chamber therein and having valved inlet and outlet passages communicating with said chamber, a rotor casing forming an annular combustion chamber, an abutment in said combustion chamber having an inclined face, a radially movable rotor piston operable in said combustion chamber over said abutment, an inwardly yieldable suction piston in said fuel storage chamber operable under influence of the radially movable rotor piston to intake and discharge fuel 55 charges from the storage chamber into the combustion chamber, an electric sparking device for igniting fuel charges in the combustion chamber and a contact member on the suction piston for closing a circuit 60 through the sparking device.

Signed at Seattle, Washington, U. S. A., this 9th day of September, 1919.

HIYOZO KAWATE.
